Dear Mr. Smith, his Atty

Inventor:

UNITED STATES PATENT OFFICE.

GEORGE B. KELLY, OF JAMAICA PLAIN, MASSACHUSETTS, ASSIGNOR TO AEOLIA COMPANY, OF NEW YORK, N. Y., A CORPORATION OF CONNECTICUT.

PAPER-FEED MECHANISM FOR PERFORATED MUSIC-SHEETS.

1,064,341.

Specification of Letters Patent. Patented June 10, 1913.

Application filed December 6, 1912. Serial No. 735,194.

To all whom it may concern:

Be it known that I, GEORGE B. KELLY, a citizen of the United States, and a resident of Jamaica Plain, in the county of Suffolk and State of Massachusetts, have invented certain new and useful Improvements in Paper-Feed Mechanism for Perforated Music-Sheets, of which the following is a specification.

10 This invention relates to improvements in paper feed mechanism for perforated music sheets and more particularly to the mechanism for properly moving the sheets lengthwise while they are being punched and the 15 object of my invention is to provide a new and improved machine of this kind which is simple in construction, compact, reliable and rapid in operation, and prevents the buckling or crinkling of the paper, by the 20 devices which grasp the paper to move it lengthwise.

In the accompanying drawing in which like letters of reference indicate like parts in all the figures: Figure 1 is a side elevation of my improved perforating machine, parts being broken away, some omitted and others shown in section. Fig. 2 is an end view of the same, parts being omitted.

My improved machine is an improvement 30 in machines of that general type shown in Patent No. 947,495 issued to myself and F. L. Wood on the 25th of July, 1910 and Patent No. 1,021,049 issued to myself on the 26th of March, 1912. Two sprocket wheels 35 1 are fixed on a shaft 2 mounted in standards 3 and two like sprocket wheels 4 are fixed on the shaft 5 mounted in standards 6. Over the sprocket wheels 1 and 4 at each side of the machine, endless sprocket chains 40 7 of conventional construction are passed and these sprocket chains are connected at intervals by cross bars 8. The upper or outer face of each cross bar 8 forms the support for the superimposed layers of paper 45 9 to be perforated. Each end of each bar 8 is embraced adjacent to its point of attachment to a chain 7 by the forked end 10 of an angular clamping lever 11 pivoted to the corresponding bar at 12 and having extensions 13 which form cams, on which the free ends of springs 14 bear, there being one spring attached to each side of each bar 8, so that one spring bears on the free end edge 55 part of each cam part 13 of each clamping lever 11 as shown in Fig. 2 of the drawings.

Two shafts 15 and 16 are mounted in the standards 3 and 6 above the shafts 2 and 5 respectively, and these shafts each carry two sprocket wheels 17 and 18 respectively and over said sprocket wheels 17 and 18 the two 60 endless sprocket chains 19 are passed.

The chains 19 are of such total length that the bottom parts or strands are not taut between the sprocket wheels but sag, as shown in Fig. 1. It will be seen from Fig. 2 that 65 the distance between the sprocket wheels 17 or 18 on the shafts 15 and 16 is much less than the distance between the sprocket wheels 1 or 4 on their respective shafts. To the two sprocket chains 19 a series of bars 70 20 are secured in such manner that they project beyond the sprocket chains and are of such length that when a bar 20 is directly upon the corresponding bar 8 of the lower set of sprocket chains it can be grasped and 75 clamped by one of the clamps. The shaft 2 is driven from the shaft 21 of the punching mechanism by means of beveled gearing 22, the shaft 23 and worm gear 24 in such a manner as to draw the upper strands of 80 the endless chains 7 in the direction from right to left. As the lower strands of the chains 19 are to be loose and are to sag the pulling strain must be on the upper strands and these must be drawn in the direction 85 from left to right by the sprocket wheels 18 on the shaft 16. The sprocket chains 7 and 19 must be driven at precisely the same speed so that the bars 20 on the upper set of endless chains will properly register with 90 the bars 8 of the lower set of chains. For this purpose a worm wheel 35 is fixed on the shaft 16 and engages a worm 36 on a shaft 37 suitably mounted and carrying at its upper end a beveled cog wheel 38 which engages a beveled cog wheel on the shaft 21 at the opposite side of the machine from the beveled gearing 22. The shaft 37 will thus be driven in the reverse direction of the shaft 23 and the upper strands of the chains 19 are pulled in the reverse direction of the upper strands of the chains 7 and the lower loose strands of the chains 19 adjacent to the upper strands of the chains 7 are thus moved in the same direction as the 95 upper strands of the chains 7.

The punching mechanism shown at 39 need not be described as it forms no part of the present invention and is merely shown for the purpose of illustrating the machine 100 110.

and furthermore this is fully described in my Patent No. 1,021,049.

To the standards 3 and 6 cams 29 and 30 are secured which, in the manner described 5 in the two patents previously mentioned serve for swinging the clamping levers 11 downward when the bars of the lowest chains have reached the highest points on the wheels 4 and for swinging these levers 10 upward when the bars on the lowest chains begin to travel downward from the highest points of the wheels 1. The bars on the two chains are so arranged that when one of the bars 8 on the lowest chains arrives in 15 the highest position upon the sprocket wheels 4, that is, directly above the shaft 5, the corresponding bar 20 on the upper chains 19 will rest directly above said highest bar 8, that is directly above the paper 20 upon said bar 8. When these two bars are so positioned, one directly above the other, the corresponding clamping levers 11 are thrown into the position shown on the top 25 bar 8, in Fig. 2, and hold the corresponding bar 20, of the upper chains, firmly upon the paper resting upon the corresponding bar 8 of the lower chains and as these clamping members are under spring pressure they are held in place in relation to the bars 8 of the 30 lowest chains and as the chains move at the same speeds the said bars 8 of the lowest chains and bars 20 of the upper chains, while clamped together, can move from right to left, Fig. 1, until the corresponding 35 clamping levers 11 are disengaged by the cam 29 and so on. The paper is thus not clamped only at each side edge of the strips or bands of paper passing through the machine but is always clamped throughout its entire width by a bar 20 of the upper 40 set of chains being clamped to a corresponding bar 8 of the lower set of chains. This prevents buckling, crinkling and folding of the paper transversely and also prevents 45 undue transverse strain on the paper and insures a uniform, regular and reliable feed.

Having described my invention what I claim as new and desire to secure by Letters Patent is:—

50 1. In a paper feed mechanism for paper perforating machines, the combination with two pairs of endless chains, sprocket wheels

for each pair of chains and bars uniting the chains of each pair of chains, one pair of chains and its bars being superimposed 55 above the other pair of chains and its bars, the chains of the lowest bar being substantially taut, and the bottom strand of each endless chain of the upper pair being slack 60 so that it can hang down between its supporting sprocket wheels and of means for driving the two pairs of chains at the same uniform speed, clamping devices on the bars on the lower pair of chains for engaging the bars on the upper pair of chains and 65 cams for alternately lifting the clamping devices off the upper bars and applying them upon the upper bars, substantially as set forth.

2. In a paper feed mechanism for perforating machines, the combination with two pairs of endless chains, bars uniting the endless chains of each pair, separate sprocket wheels for each pair of chains, one pair of chains being superimposed above the other, 70 clamping means on the ends of the bars of one pair of sprocket chains, for clamping the bars on the other pair of sprocket chains, and means for alternately applying and disengaging the clamping means, and 75 independent means for each pair of chains for driving both pairs of chains at the same speed, substantially as set forth.

3. In a paper feed mechanism for paper perforating machines, the combination with 80 a pair of endless chains, sprocket wheels over which the chains are passed, bars uniting the chains and secured between the chains, a series of bars located parallel to the bars on said chains and located above 85 the same, chains connected with said upper bars, between the ends of these bars, locking means for locking the bars of the upper pair of chains on the bars of the lower pair of chains and means for alternately applying 90 and disengaging these locking devices, substantially as set forth.

Signed at New York city, in the county of New York and State of New York this 24th day of September A. D. 1912.

GEORGE B. KELLY.
